UNITED STATES PATENT OFFICE

90,981

DESIGN FOR A CAKE BOX

James A. Greene, Atlanta, Ga., assignor to American Bakeries Company, Atlanta, Ga., a corporation of Georgia

Application August 31, 1933. Serial No. 49,178

Term of patent 14 years

To all whom it may concern:

Be it known that I, JAMES A. GREENE, residing at Atlanta, county of Fulton, State of Georgia, have invented a new, original, and ornamental Design for a Cake Box, of which the following is a specification, reference being had to the accompanying drawing, forming part thereof.

The figure is a perspective view of a cake box showing my new design.

I claim:

The ornamental design for a cake box, as shown.

JAMES A. GREENE.
